MULTIPLE HULL EXTRACTOR

Jeffrey John Wallace, Amite, La., assignor to
 Gullett Gin Company, Amite, La., a corpora-
 tion of Louisiana

Application August 20, 1934, Serial No. 740,712

4 Claims. (Cl. 19—37)

This invention relates generally to machines for separating hulls from cotton, and more particularly to hull extracting cleaning feeders of this type.

5 The general object of the invention is the improvement of cotton hullers by employing multiple extraction instrumentalities in association with a single saw cylinder, thus minimizing the size of the complete machine and at the same time increasing its efficiency.

Another object of the invention is to provide a novel cleaning drum for effecting the distribution of the cotton in a uniform layer or fleece widthwise of the drum and constructed so as to 10 constitute a fan for creating a draft of air contrary to the direction of travel of the incoming cotton whereby to aerate and loosen the cotton relative to the hulls and hull debris.

Still another object of the invention is to provide a distributing system within the machine so that a thin uniform flow is maintained and presented to the saw cylinder, thus preventing the incoming mass from forming a bulky semi-solid body from which the hulls cannot be readily removed.

25 A further object of the invention is to provide screening surfaces at strategic points for removing sand, leaf trash and other foreign matter from the cotton.

Another object of the invention is to provide 30 for multiple presentation of the hulls to the lower side of the saw cylinder in the hull discharge outlet for removing the small locks of cotton which generally are adherent to or intermingled with the hulls.

35 A further object of the invention is the positioning of the stripper cylinder or cylinders in relation to the saw so that each stripper returns the surplus cotton removed from the saw cylinder separately to the respective cleaning drums to be returned to the incoming stream of cotton to be re-distributed and re-presented to the saw cylinder.

Another object of the invention is to provide 45 an improved type of doffer in which rubber strips or vanes are substituted for the customary bristles and with advantageous results both as to the removal of the cotton and the longevity of the doffer.

50 Still another object of the invention is the provision of feeding means operated directly from the saw cylinder with means for regulating the capacity of the feeding means to correspond to the demands of the saw cylinder.

55 Other objects of the invention will appear as

the following description of a preferred and practical embodiment thereof proceeds.

In the drawings which accompany and form a part of the following specification and throughout the several figures of which the same characters of reference have been employed to designate identical parts:

Figure 1 is a vertical section through the hulling machine in a plane perpendicular to the axes of the rotating parts;

Figure 2 is a view in elevation of the end of the machine nearest the observer;

Figure 3 is a similar view showing that end of the machine remote from the observer;

Figure 4 is a perspective view of one of the 15 cleaning rolls, part being omitted;

Figure 5 is a perspective view of the doffer, part being broken away;

Figure 6 is a cross section through one of the strippers;

Figure 7 is a perspective view of one of the stripper blades; and

Figure 8 is a fragmentary view in section taken along the line 8—8 of Figure 2.

Referring now in detail to the several figures it will be understood that the machine comprises a casing 1 having opposite end walls 2 and 3. The raw cotton together with the bolls and such other debris as may be entrained with it is admitted through a suitable opening 4 at the top 30 of the casing. There are two exits, one for the cotton and the other for the hulls. The former designated by the reference character 5 is for the discharge of clean cotton and is at the distal end of a system of cooperating rotating members 35 as will in due course be described. The exit 5 is provided with a discharge chute 6 which may be angularly adjusted by means of a pin, not shown, selectively cooperating with any one of the indent 7. The chute as shown is pivoted at 8, 40 but this is an immaterial detail.

The hulls, sand and other debris are discharged by means of a screw conveyor 9 at the bottom of the casing.

Within the casing, and mounted on parallel 45 shafts are a pair of cooperating feed rollers 10 and 11 with a space between them to allow ingress of the cotton. The arrows show that these rollers rotate in opposite directions. A primary cleaning drum 12 is positioned at a lower level 50 than the feed rollers, and by preference, symmetrical with respect to the space between said rollers. A secondary cleaning drum 13 is rotated to one side of the primary cleaning drum 12 and at a distance therefrom. Suitably shaped parti-

- tions 14 and 15 are placed adjacent the cleaning drums so as to determine that said drums shall act in serial order upon the incoming stream of cotton. The cotton descends upon the cleaning drum 12, is whisked through the space between said drum and the partition 14, and then upward through the space between said drum and the partition 15 and thrown over upon the drum 13. That part of the side wall of the casing adjacent the cleaning drum 13 is formed as a hinged conduit 16 having inner and outer walls 17 and 18, respectively. The upper part of the inner wall 17 is formed as a screen 19 and preferably made of perforated sheet metal.
- When the hinged conduit is in the closed position relative to the casing, its lower open end 20 discharges into said casing. The incoming cotton after having passed the cleaning drum 12 in the manner described, and having been thrown upon the cleaning drum 13, is carried by said drum through the passage between the drum 13 and the screen 19. The incoming material is scoured against the screen 19, the sand and small trash being thrown off by centrifugal force through the screen 19. The solid wall 17 or apron below said partition prevents the foreign material that has been thus removed by the cleaner drum 13 from re-entering the stream of cotton that is within the machine.
- The cleaning drum 13 has a triple function, first, to receive the cotton from the partition 15 and present the same to the screen 19; second, to pitch the incoming material downward on to the saw cylinder 21 and impinge the same on the saw teeth of said cylinder or their equivalent; third, to receive the surplus of cotton and hulls which are stripped from the saw cylinder, as will appear.
- The location and function of the cleaning drum 13 is an important feature of the invention as well as the relative length of the screen 19. Said length is such that a line perpendicular to a radius of the cleaning drum 13 extending in the direction of the lower edge of the screen 19 shall strike the saw cylinder at approximately from 20 to 30 degrees above the horizontal diametrical plane of said saw cylinder and above the hull outlet and by-pass valve 26 which is located adjacent the mouth of the hinged conduit 16.
- The importance of this particular construction is that due to centrifugal force of the cleaning drum 13, the heavier particles and harder substances in the cotton will be carried on the side next to the screen or on the outside of the stream of material being carried by said cleaning drum. This heavier and harder substance will follow downward along the imperforate inner wall 17 and fall through the opening 27 between the by-pass valve 26 and the saw cylinder. The size of said opening is regulated by the position of the valve 26, which valve is regulated from the outside of the machine by means of the reciprocable handle bar 28 pivotally connected to a crank 29 fixed to the shaft 30 of said by-pass valve. When the valve 26 is in its fully opened position indicated by the broken lines, the heavier material and hulls will readily enter into the secondary extraction chamber 31. The cotton being less heavy than the harder substance will be thrown downward from the cleaning drum 13 at a less angle as is graphically indicated by the line *a*, impinging upon the saw cylinder. Thus, a centrifugal classification of the harder foreign material and the cotton is performed by the cleaning drum 13.

At this point, the description will revert to the structure of the feeding rollers 10 and 11 and the cleaning drums 12 and 13. The feeding rollers are preferably triangular in shape as shown, each being formed of three plates of V-shaped cross section, the apices of said plates extending longitudinally for the entire length of the rollers. The ends of the plates are bent up angularly into flanges 22 which are bolted together. Thus the surfaces of the feeding rollers are formed alternately of longitudinal dihedral angles and longitudinal flanges which inter-gear themselves with the incoming cotton and feed it in a positive manner to the interior of the machine.

Each of the cleaning drums is preferably formed of a plurality of angularly bent plates 23 having radially extending abutting flanges 24 by means of which the several plates constituting the drum are secured together. On those faces of the drum which alternate with the faces having the flanges, are a series of pins 25. The flanges act as fan vanes to create a draft of air to aerate the incoming cotton, and the pins have the function of a comb, to maintain uniform distribution of the cotton from the incoming stream of cotton.

The saw cylinder 21 is of conventional construction, being formed either of disks 32 of card clothing, separated by spacing segments 33, or it may be constructed of ordinary channel type, if desired.

The cotton projected upon the saw cylinder from the cleaning drum 13 is carried circumferentially upon the surface of said saw cylinder in the direction of the arrow 34, being added to by the hull cleaning drums 35 and 36 and subtracted from by the stripper rolls 37 and 38. The clean cotton reaches the final side of the saw cylinder 21 where it is removed by the doffer 39 and delivered by the doffer to the final cleaning drum 40 which is similar in construction to the cleaning drums 12 and 13, previously described. The doffer and the cleaning drum 40, respectively, scour the cotton against a screen 41 by centrifugal force, ridding it of the final traces of foreign substance. The cotton is finally discharged through the chute 6.

Now, referring to the stripper rolls 37 and 38, they are provided with plates 42. The incoming stream of cotton and hulls thrown downward upon the saw cylinder by the cleaning drum 13 is carried upward by the saw cylinder into contact with said plates. The stripper rolls knock back the surplus cotton and hulls. The distance between the edges of the stripper plates and the teeth or filaments of the saw cylinder being in close proximity to each other, the greater portion of the hulls is removed from the cotton at this point. The stripper roll 38 strips off such hulls as may have been carried past the stripper roll 37. The stripper rolls 37 and 38 are so located that the cotton and remaining hulls which they knock off of the saw cylinder 21 are thrown upward on the opposite sides of the partition 15, engaging in the stream of incoming cotton, passing from the cleaning drum 12 to the cleaning drum 13, being again re-distributed and subjected again to the entire process of cleaning and separating.

The hull cleaning drums 35 and 36 are located in the hull chamber 34 beneath the saw cylinder 21, and are preferably provided with rows of curved spikes 73. The hull cleaning drum 35 receives the material, mostly hulls, but with small locks of cotton adherent thereto, coming through

the opening 27 between the by-pass valve 26 and the saw cylinder. The lower wall of the chamber 31 is constituted by a hinged hull conduit 43, the inner wall of which is a screen 44 preferably shaped with depressions forming pockets which partially surround the hull cleaning drums 35 and 36. The direction of rotation of the drum 35 is opposite to that of the saw cylinder 21 so that the material impinging upon the drum 35 is scoured against the screen 44, the centrifugal action of the drum 35 forcing the heavier material and hulls downward on this screen and removing the smaller particles of trash through this screen. The hulls being harder, will rebound further from the impact of the spikes than the cotton which is soft and spongy, the hulls being kicked into the pocket of the screen 44 which partially surrounds the drum 36 while the soft spongy material is impinged upon the saw cylinder 21 and carried around upon said saw cylinder.

The hulls and a small amount of one seed cotton locks which have been shot into operative relation to the hull cleaning drum 36 are given a final scouring against the adjacent portion of the screen 44. The foreign matter which has passed through the screen 44 descends by gravity through the hinged conduit 43 and enters the chamber of the conveyor 9.

The function of the drum 36 is approximately the same as that of the drum 35 excepting that due to the shape of the screen pocket beneath and which partially surrounds this drum, the entire mass moved by said drum is thrown upward against the saw cylinder 21. The harder and heavier substances such as hulls, will not adhere to the saw cylinder and fall off into the conveyor chamber.

The doffer 39 is provided with flexible blades 45 which engage the cotton on the saw cylinder with a wiping action by which it is readily removed. The flexible material of the blades, which may be rubber, is more adherent with respect to the cotton than metal would be, and the removal of the cotton is thus more efficient. The screen 41 against which the cotton is scoured by the doffer and the final cleaning drum 40 constitutes the inner wall of a hinged conduit 46 and the debris which passes through the screen 41 gravitates down the outer wall of the conduit 46 into the chamber of the conveyor 9.

It is obvious from the above description that all three of the screened conduits 16, 43 and 46 can be swung to open position, giving access to the interior mechanism of the machine, and particularly to the screens 19, 44 and 41 so that the latter can be readily cleaned.

The several rotating members which have been described are mounted upon parallel shafts journaled in the opposite end walls of the casing. Power is delivered to the machine by means of a pulley 47 on the end of the shaft 48 of the cleaning drum 12. The opposite end of said shaft carries a pulley 49 engaged by a belt 50 which follows a sinuous course about various pulleys which it is unnecessary specifically to mention on the ends of the shafts by which the several rotary members are driven, with two exceptions. The pulley 51 about which the belt 50 passes is merely an idler provided for the purpose of bringing the belt about a large arcuate portion of the power pulley 49. Figure 8 shows that the idler pulley 51 is journaled upon a stud bolt 52 on the end of the shaft 53 which carries the feed roller 10. Consequently, the said feed roller is relieved from the continuous

drive of the belt. The two said rollers 10 and 11 are operatively connected by means of gears 54 and 55 fixed respectively on the shafts 53 and 56. On the opposite end of the shaft 56 is a ratchet gear 57. This gear is intermittently actuated and consequently, the rotation of the feed rollers is intermittent. Step by step movement is imparted to the ratchet gear 57 by means of a pawl device constituting a rod 58 swinging about a fulcrum 59, and on said rod and oscillatable therewith is an arcuate support 60 pivotally carrying at one end, the advancing pawl 61 and pivotally carrying at the other end, the holding pawl 62. In that form of the invention disclosed by way of illustration, the holding pawl 62 is kept in contact with the teeth of the ratchet gear by a weight 63. The advancing pawl is also mounted in an unbalanced manner so as to be held against the ratchet gear by gravity. As the rod 58 oscillates, the pawl 61 is first dragged down over the sloping surfaces of the ratchet teeth and then pushed in a contra direction against the abrupt faces of said teeth, imparting a partial rotation to the ratchet gear. Oscillatory movement is transmitted to the rod 58 by means of a connecting rod 64 pivotally connected at one end to a sleeve 65 which slides on said oscillating rod, and rigidly connected at its opposite end to an eccentric 66 on the end of the shaft 67 of the saw cylinder. Thus, as the saw cylinder rotates, the feeding rollers revolve, step by step.

In the event that the operation of the feed rollers must be adjusted to suit the capacity of the saw cylinder to dispose of the cotton, a handle 68 is provided which may be moved up and down along the rod 58, carrying with it the sleeve 65. When the sleeve is near the fulcrum 59, the amplitude of travel of the pawl is greater than when the sleeve is remote from said fulcrum.

The saw cylinder 21 is preferably driven by a gear 69 on the opposite end of the shaft 67 to that on which the eccentric is mounted. The gear 69 is in mesh with a small gear 70 at one end of a shaft 71 which is driven from the common belt 50 through a pulley 72.

In operation, the raw cotton including the bolls or hulls is fed to the inlet 4, the triangular sides of the feed rollers 10 and 11 acting as the sides of a hopper. The rate of feeding of the cotton from the rollers into the machine is manually regulated by sliding the handle 68 in one or the other direction along the rod 58 which oscillates the feeding ratchet. The entering cotton is delivered upon the cotton cleaning drum 12 where it is combed out into a wide flat sheet by the rows of pins 25. The cotton is kept loose and free by a draft created by the flanges 24 through the rotation of the cleaning drums. The sheet of cotton is carried down along the partition 14 and up along the partition 15, receiving the accretion of surplus cotton from the stripper roll 38 which is located in the space between the two partitions. The sheet of cotton then proceeds to the cotton cleaning drum 13 receiving the accretion of return cotton from the stripper roll 37. The sheet of fleece of cotton is whirled around the cleaning drum 13 into contact with the perforated wall 19 of the conduit 16 where as has been previously stated, the sand and small trash is thrown through to the said conduit. Said sand and small trash falls through the conduit 16 entirely segregated from the cotton and hull streams, and gravitates upon the 75

anterior part of the screen 44, passing through said screen into the conduit 43, and into the hull discharge conveyor 9. Such sand and small trash as does not go through the screen 44 by 5 gravity is driven through it by the action of the spikes 13 on the hull cleaning drums 35 and 36. The cotton and hulls which, as stated, have been whirled past the perforated screen 19 separate centrifugally through their difference in weight, 10 the fluffy and lighter cotton shooting down along the line a upon the saw cylinder 32 impinging upon the teeth or filaments thereof. The hulls being heavier, are thrown out against the partition 17 and travel down close to said partition 15 until they strike the valve 26. The position of the valve is adjusted according to the volume of descending hulls to bring them into proper proximity to the cleaning drum to permit the latter to remove as much as possible of the adherent 20 cotton. The hulls then drop upon the first or anterior of the hull cleaning drums 35. The arrow in Figure 1 denotes the direction of rotation of this drum, the hulls being dashed against the screen 44 where any particles small enough to 25 pass through said screen are thus eliminated and the hulls are crushed or broken so as to free more of the adherent cotton. The rate of rotation of the hull cleaning drum is such that the hull particles are shot across the space between the two 30 hull cleaning drums upon the rearward hull cleaning drum 36. The entire mass received by the hull cleaning drum 36 is carried around by said drum and thrown centrifugally against the saw cylinder where the lint catches in the teeth 35 of the saw cylinder while the hulls rebound from said saw cylinder into the underlying hull discharge conveyor 9.

Meanwhile, the saw cylinder, rotating in a clockwise direction as viewed in Figure 1, has accumulated a peripheral layer of cotton received directly from the cotton cleaning drum 13 and having been added to by the hull cleaning drums 35 and 36. To prevent this layer of cotton from becoming so thick that it will be compacted as a 45 semi-solid mass upon the surface of the saw cylinder, the stripper rolls 37 and 38 are provided. The roll 38 is at a slightly closer distance to the surface of the saw cylinder than the stripper roll 37. Thus excess layers of cotton are removed successively by the stripper rolls 37 and 38 and returned as has been described to the respective 50 cotton cleaning drums 13 and 12. Thus, when the saw cylinder reaches the doffer 39, it has just the right thickness of cotton upon it to be removed by said doffer. The latter element has flexible 55 blades preferably of rubber which wipe the cotton from the teeth or filaments of the saw cylinder in the direction indicated by the arrow in Figure 1, the cotton being brought forcibly against the screen 41 centrifugally through the rotation of the doffer. Here, any adherent particles are expelled 60 through the screen 41 into the conduit 46 from which they gravitate into the discharge conveyor. The doffer delivers the cotton to the final 65 cleaning drum 40 where it is combed and fanned and discharged through the chute 12, any remaining debris passing through that part of the screen 41 which underlies the cleaning drum 40.

While I have in the above description disclosed 70 what I believe to be a preferred and practical embodiment of my invention, it will be understood that the details of construction as shown and described are merely by way of example, and not to be construed as limiting the scope of the invention as claimed.

What I claim is:

1. Cotton huller comprising a single saw cylinder, feeding means, a pair of cotton cleaning drums arranged serially between said feeding means and saw cylinder, and a pair of stripper rolls arranged adjacent said saw cylinder, independently taking excess cotton therefrom and delivering it to respective cotton cleaning drums, the latter having means for entraining the returned cotton with the incoming cotton stream. 10

2. Cotton huller comprising a single saw cylinder, feeding means, a pair of cotton cleaning drums arranged serially between said feeding means and said saw cylinder, a pair of stripper rolls arranged adjacent said saw cylinder, independently taking excess cotton therefrom, a partition shaped to cooperate with said stripper rolls and said cotton cleaning drums whereby the cotton removed by said stripper rolls from said saw cylinder is directed toward respective cotton 20 cleaning drums, the latter having means for entraining the returned cotton with the incoming cotton stream.

3. Cotton huller comprising a casing having a cotton inlet, a cotton discharge and a hull discharge, means establishing a cotton traversing route and a hull traversing route, said routes leading respectively to the cotton discharge and the hull discharge, the hull traversing route branching from the cotton traversing route, said 25 means including a rotatable cleaning drum and a cooperating wall, said wall curving relative to said cleaning drum in spaced relation thereto, forming a cotton and hull passage, and having an apron extending downward from said curved 30 portion determining the path of descent of hulls thrown centrifugally against said wall by said cleaning drum, said apron diverging from the trajectory of the cotton thrown off by said cleaning drum, a saw cylinder positioned so as to intersect the trajectory of the path of the cotton, but out of the hull path determined by said apron, said cooperating wall and cleaning drum thus 35 determining the point of departure of said hull traversing route from said cotton traversing route, 40 said casing including a conduit of which said wall forms the inner side, having an open lower end, the curved portion of said wall being formed with perforations letting sand and small trash 45 into said conduit, said casing including also a screen beneath said saw cylinder in the path of sand and small trash descending from said conduit and anterior and posterior hull cleaning drums between said screen and saw cylinder in 50 said hull traversing route, said screen being formed with two flights, the anterior flight having a forward portion curving around the anterior hull cleaning drum, and a rear portion parallel to a line tangent to said anterior hull cleaning drum and directed toward the posterior hull 55 cleaning drum, whereby heavier particles are thrown into engagement with said posterior hull cleaning drum, said anterior hull cleaning drum functioning to force debris through said screen and to throw the cotton released from the hulls 60 into contact with said saw cylinder.

4. Cotton huller comprising a casing having a cotton inlet, a cotton discharge and a hull discharge, means establishing a cotton traversing route and a hull traversing route, said routes leading, respectively, to the cotton discharge and the hull discharge, the hull traversing route branching from the cotton traversing route, said means including a rotatable cleaning drum and a cooperating wall, said wall curving relative to said clean- 75

ing drum in spaced relation thereto, forming a cotton and hull passage, and having an apron extending downwardly from said curved portion determining the path of descent of hulls thrown centrifugally against said wall by said cleaning drum, said apron diverging from the trajectory of the path of the cotton thrown off by said cleaning drum, a saw cylinder positioned so as to intersect the trajectory of the path of said cotton, but out of the hull path determined by said apron, said cooperating wall and cleaning drum thus determining the point of departure of said hull traversing route from said cotton traversing route, said casing including a conduit of which said wall forms the inner side, having an open lower end, the curved portion of said wall being formed with perforations letting sand and small trash into said conduit, said casing including also a screen beneath said saw cylinder in the path of sand and small trash descending from said conduit, and anterior and posterior hull cleaning drums between said screen and saw cylinder in said hull traversing route, said screen being formed with two flights, the anterior flight having a forward portion curving around the anterior hull cleaning drum and a rear portion substantially parallel to a line tangent to anterior hull cleaning drum and directed toward the posterior hull cleaning drum whereby heavier particles are thrown into engagement with said posterior hull cleaning drum, said anterior hull cleaning drum functioning also to force debris through said screen and to throw the cotton released from said hulls into contact with said saw cylinder, the terminal portion of the second flight lying adjacent the hull discharge and curving upwardly about the lower portion of said posterior hull cleaning drum, the latter functioning to throw the entire mass of cotton and hulls upwardly in contact with said saw cylinder, the teeth on said saw cylinder engaging the loose lint cotton while the hulls rebound off the saw cylinder and fall into the hull discharge.

JEFFREY JOHN WALLACE.
